VARIABLE TUNING CONDENSER

Joseph Antonietta, Port Richmond, N. Y.

Original application March 28, 1933, Serial No. 663,120, now Patent No. 1,972,510, dated September 4, 1934. Divided and this application November 3, 1933, Serial No. 696,472

8 Claims. (Cl. 175—41.5)

This invention relates to variable condensers, and particularly to devices of this character used for tuning as in radio apparatus.

One object of the invention is to devise a variable condenser having an improved mounting or shaft construction for the rotor plates, whereby the rigidity of the rotor plate is increased, lightness in the weight of the shaft maintained, or rendered less than the weight of the usual round 10 or solid shaft, and which shaft can be formed from sheet material, if desired.

Another object of the invention is to construct a variable condenser having improved similar means for mounting the shaft at opposite ends 15 thereof; improved means for mounting and insulating the stator plates; improved means for reinforcing the frame of the condenser; and improved closure means for the condenser; the above feature being adapted for utilization in any 20 desired arrangement or combination.

A further object of the invention is to furnish an improved condenser having few and simple parts, and which is compact and inexpensive in construction, convenient to make and use, and 25 durable, reliable, and efficient in operation.

This is a divisional application based on my Patent No. 1,972,510, issued September 4, 1934.

Other objects and advantages of the invention will become apparent as the specification 30 proceeds.

With the aforesaid objects in view, the invention consists in the novel combinations and arrangements of parts hereinafter described in their preferred embodiments, pointed out in the 35 subjoined claims, and illustrated on the annexed drawing, wherein like parts are designated by the same reference characters throughout the several views.

In the drawing:

Figure 1 is a view in front elevation of a device embodying the invention with parts removed to show the internal construction.

Fig. 2 is a view in side elevation thereof.

Fig. 3 is a top plan view thereof, with parts removed, and other parts being in section.

Fig. 4 is a longitudinal sectional view of the shaft taken on line 4—4 of Fig. 3.

Fig. 5 is a transverse sectional view of the 50 shaft taken on line 5—5 of Fig. 3 and showing a condenser rotor plate in dot-dash lines.

Fig. 6 is a horizontal sectional view taken on line 6—6 of Fig. 2.

Fig. 7 is a fragmentary plan view of a rotor 55 condenser plate.

Fig. 8 is a fragmentary horizontal sectional view of the shaft taken on line 8—8 of Fig. 4.

The advantages of the invention as here outlined are best realized when all of its features and instrumentalities are combined in one and the 5 same structure, but useful devices may be produced embodying less than the whole.

It will be obvious to those skilled in the art to which this invention appertains, that the same may be incorporated in several different constructions. The accompanying drawing, therefore, is submitted merely as showing the preferred 10 amplification of the invention.

Referring in detail to the drawing, 10 denotes a device embodying the invention. The same 15 may include a frame having a plurality of parallel end plates 11, 12 of similar form, and whose upper edges 13 may be arc shaped to conform to the shape of the rotor plates of the condenser. Interconnecting said end plates there may be a 20 one piece frame member of generally U shaped form, and having a bottom plate section 14 and upright side plate sections 15 that may be exactly alike. The frame member may be spaced somewhat inward of the adjacent side edges 16 of 25 the end plates, and the side sections 15 may have marginal outwardly bent flanges 17 extending thereto along the edges 16. The frame members 14, 15 may lie in abutment between the end plates, and may be secured thereto as by the usual lugs 30 18 passed through suitable openings in the end plates and deformed or headed to form a strong interconnection. If the condenser is of a double section type, a plate 19 may be provided intermediate of and parallel to the end plates and of 35 generally similar shape therewith. Said intermediate plate may be secured in place in any suitable manner as by lugs 18 engaging frame section 14, and it may be undercut to lie between frame sections 15 and conform to the flanges 17, as will 40 be obvious. To provide a closure for the condenser frame or housing, a cover 20 may be utilized, and which may consist of an arcuate resilient or flexible sheet of metal adapted to seat on the curved edges 13 of the end plates 11, 12, and 45 having longitudinal parallel lips 21 adapted to be snapped under the flanges 17 for retaining the cover in place.

For mounting the device on the chassis of a radio apparatus, the frame section 14 may have 50 bosses 22 downwardly struck to the plane of the lower edges 23 of the end plates, and threaded as at 24 for receiving screws. Should there be any irregularity in the chassis or frame, the latter would be sprung by the tension of the screws at 55

24 and hence the frame would become distorted and the spacing between the condenser plates affected, as hereinafter more particularly described. Such distortion, however, is prevented 5 by the flanges 37 which afford a strong and simple reenforcement where it is most needed.

The variable condenser includes a stator having one or more plates 25 and a rotor having one or more plates 26, suitably arranged in alternating 10 but spaced relation, and being each in the form of a sector or semicircle, and disposed in parallel planes, whereby, on angularly moving the rotor, the capacity of the condenser is varied. It will be particularly noted that the stator and rotor 15 plates are concentrically symmetrically arranged, whereby a high degree of compactness is afforded, the rotor requiring a minimum of space for its path of travel, so that the cover 20 becomes practical to apply. Heretofore, condensers arranged 20 to change the capacity thereof at variable rates have been arranged with the condenser plates disposed according to an eccentric principle, so that the rotor requires a higher path of travel and therefore more space in a radio apparatus, 25 and hence such condensers were not provided with a cover.

For mounting the stator plates, the same may be formed with arcuate segments 27 which may be suitably secured to the angular plates 28. In 30 order to insulate the stator from the frame, the plates 28 may be engaged with plates of insulation 29, as by screws 30, and terminal contacts 31 may also be affixed to said screws. In the opposed side frame sections 15, openings 32 may be provided. 35 Along the upper and lower edges of said openings, lugs 33 may be pressed inward and with their ends slightly toward each other, and along the side edges of said openings, lugs 34 may be pressed inward and curved to afford an entrance. In providing lugs 33, flanges 35 may be formed along the upper and lower edges of said openings. The plates 29 are snugly fitted in seating engagement between the several lugs 33, 34 and so as to rest against the flanges 35, being so maintained 40 by reason of the abutment action of the stator and plates 28 between the opposite insulating plates 29. The plates 28 may be slightly resilient if desired to afford a snug wedging fit. Heretofore the plates 29 have been riveted to the frame. 45 This required the use of non-brittle materials of low insulating qualities. By my invention, the expense of riveting is avoided, and plates 29 of high insulating character may be employed, which are reliably and quickly secured in place.

50 For mounting the rotor plates 26, a means 36 may be provided which may in certain respects be denominated a shaft, and in other respects a frame or plate. The same may have rib or flange means 37, and is desirably made of channel form 55 in cross section, and is preferably made of a sheet of material such as metal. Thus a sheet of plane material may be bent and slotted in a single operation to produce the means 36. One possible embodiment of the invention, preferably includes 60 the flange and channel features, the latter being designated by 38, and including a back 39 and side walls or flanges 40 from which one or more of the marginal lips or flanges 37 extend radially, as along a plane passing through the axis of rotation 65 of the shaft. The back 39 may be transversely slotted as at 41, and the flanges 37 may have slots 42 alined with different slots 43, the slots 42 extending preferably to the side walls of the channel. Intermediate of the ends of the shaft, the 70 flanges 37 may be cut away as at 43, if desired,

to afford clearance for the intermediate plate at an opening 44 thereof which may form a part of a slot 45 that clears the shaft so that the rotor unit can be dropped into the frame to be assembled therein.

5 By means of the lips 37, the rotor plates are reenforced along a greater length, and increased rigidity thereof is obtained.

For fixing the rotor plates to the shaft, each rotor plate may have an opening 46 adapted to 10 receive the shaft and having edge portions 47 and 48 at said opening fitted in the respective slots 41, 42 of the shaft and bearing against the side walls of the channel shaft section. For strongly securing the rotor plates in the slots, a force 15 may be exerted on the outside of the back of the channel between the different rotor plates, and if desired, the flanges 37 may be deformed slightly, whereby the metal between the different slots 41, 42 is caused to tightly pinch and permanently 20 hold the rotor plates.

For mounting the shaft 36, any suitable means may be employed, and preferably said shaft is provided with integral tongues 49, 50 at opposite ends thereof, and which may extend from the 25 back of the channel structure. Said tongues may be bent as at 51 so as to lie in square abutment with the ends of the side walls or flanges 40 of the channel structure. To afford frictionless bearing means for the shaft, the elements 49, 50 30 may be formed with alined openings or recesses 52 that open outwardly in opposite directions to afford seats for bearing members such as anti-friction balls 53, the end walls 11, 12 having means affording corresponding alined seats for 35 the balls. Thus the end wall 12 may have a similar seating recess 54, and, in order to provide for adjustment in the bearing, the end wall 11 may have a set screw 55 threaded therein and secured by a locknut 56, the set screw having a seat- 40 ing recess 57 for the adjacent ball 53.

For electrical connection with the rotor condenser plates 26, a means such as a contact member 58 that may be in the nature of a leaf spring 45 is utilized. The same may have an eye 59 pressed therefrom and fitted in a corresponding hole in the end plate 11. One end portion of the spring may have a fork 60 taking about an adjacent ball 53 and bent laterally so that the end of the fork presses against the end plate 11, and another 50 part of the fork presses against the end wall 49 of the shaft 36. The other end of the leaf spring is formed with a terminal hole 61 and projects beyond the end wall 11, the cover 20 having an 55 open ended slot 62 for receiving the same. The spring 58 also serves to reduce any possible axial movement of the rotor, and facilitates the adjustment setting of the device at the screw 55.

It will be appreciated that according to my 60 invention both bearings for the shaft are simple, compact, and similar in construction.

To provide a simplified means for causing angular movement of the shaft 36, the tongue 50 may be sufficiently elongated to constitute a crank 65 arm. The latter may have a crank pin 63 extending through an opening or arcuate slot 64 in the front plate 12. The slot 64 is so arranged that the ends thereof afford stops for the pin 63 in the position of maximum capacity of the condenser shown in Fig. 1, and in the position of zero capacity of the condenser. Hence the stop engagement heretofore used for the condenser rotor plates directly is eliminated, and any strain taken 70 up solely by the shaft. It will be noted that the

crank 50 may extend in parallelism with the straight edges 65 of the rotor plates.

To actuate the pin 63, a cam means 66 is preferably provided. The same may for compactness consist of a sheet of plane material parallel to the wall 12, and may desirably be fixed upon a sleeve 67, which may be journaled upon a bar or stub shaft 68 secured to the wall 12, as at 69, in spaced relation to the axis of the shaft 36. To 10 the sleeve 67, a conventional manual control knob and a dial with uniform graduations, not shown, may be removably fitted in any well known manner. To provide for removability and interchangeability of the cam 66, the outer end of 15 the stub shaft 68 may have an annular groove 70, and a washer 71, slotted at 72, may be removably snugly engaged therein to slidingly abut the end of the sleeve 67.

The cam means 66 may include an open ended 20 fork 73 for slidingly receiving the pin 63. This fork may have any desired cam slope 74. To avoid backlash in the cam engagement, an opening 75 may be formed spaced from the closed end of the fork and connected therewith by a 25 narrow opening 76, whereby the prongs of the fork are resiliently movable toward each other for snugly engaging the pin 63.

It will be appreciated that various changes and modifications may be made in the device as shown 30 in the drawing, and that the same is submitted in an illustrative and not in a limiting sense, the scope of the invention being defined in the following claims.

I claim:

35 1. A variable condenser including a rotor condenser plate, and a shaft of sheet metal of substantially channel shape, said shaft having longitudinal integral radial lips extending along the flanges of the channel, said channel having a 40 transverse slot in the back thereof and alined slots in said lips, and said rotor plate being fitted in said slots for mounting on the shaft.

2. A variable condenser including a stator plate, a rotor plate, a shaft on which the rotor plate 45 is mounted for angular movement, a frame having opposed frame members, said frame members having openings therein, flanges along the edges of said openings, laterally bent spaced lugs at the edges of said openings, plates of insulation 50 within the frame at said openings fitted between said lugs and resting against said flanges, means for mounting the stator plate on said plates of insulation so as to maintain the latter in engagement with said lugs and flanges, and terminal 55 means for said stator plate on one of said plates of insulation.

3. A variable condenser including a rotor condenser plate, and a channel shaft the flanges

whereof are provided with longitudinally extending marginal lips projecting in different directions away from each other, said lips having alined transverse slots and said shaft having another part provided with a transverse slot 5 alined with the first mentioned slots, and the rotor plate being secured in said slots, whereby the portion of the rotor plate adjacent to said shaft is rigidly held substantially throughout, as set forth.

4. A variable condenser including a rotor condenser plate, and a channel shaft having a back having a transverse slot, said channel shaft having a flange provided with a longitudinal marginal lip having a transverse slot, said lip projecting outwardly and laterally of said flange, and the rotor plate being fitted in said slots, as set forth.

5. A variable condenser including a stator plate, a rotor plate, a shaft on which the rotor plate 20 is mounted for angular movement, a frame having opposed frame members, said frame members having openings therein, flanges along the edges of said openings, laterally bent spaced lugs 25 at the edges of said openings, plates of insulation within the frame at said openings fitted between said lugs and resting against said flanges, means for mounting the stator plates on said plates of insulation, as set forth.

6. In a variable condenser in combination a plurality of rotor plates each having a hub receiving depression and having projecting tongues on opposite sides thereof and at the bottom thereof, a hub formed by a comb of strip material bent to substantially U shape, and having oppositely extending wings having openings therein to receive said tongues, whereby said plates are secured to said comb, and said comb having ears at opposite ends thereof folded upwardly to define a trough, said hub-plate assembly being supported by said ears.

7. A device including a channel member, a plate secured to the back thereof, the channel member having a lip extending along a flange thereof, said lip having a transverse slot open ended at the free edge of the lip, and said plate being additionally secured to the channel member in said slot.

8. In a variable condenser, a plate, and a shaft of sheet metal of substantially channel shape 50 providing longitudinal flanges, one of the latter having an outward extending marginal lip, said lip and the back of the channel having transverse elongated narrow openings at one side of the shaft, said plate being clampingly secured in 55 said openings.

JOSEPH ANTONIETTA.
